UNITED STATES PATENT OFFICE.

WILLIAM H. ROYSTONE, OF NEW YORK, N. Y.

VANITY CASE FOR LOOSE POWDER.

Application filed January 17, 1923. Serial No. 613,108.

To all whom it may concern:

Be it known that WILLIAM HERBERT ROYSTONE, a citizen of the United States, residing at 216 West 18th Street, New York city, borough of Manhattan, county and State of New York, has invented new and useful Improvements in Vanity Cases for Loose Powder, of which the following is a specification.

10 This invention relates to vanity cases and more particularly toward a type of vanity case for carrying loose face powder and the like. These cases should be designed so as not to be cumbersome and yet they should 15 provide the user with an adequate supply of powder so that they need not be replenished at too frequent intervals. Many users of face powder desire a loose powder, instead of a compact, for the reason that they 20 can then have a wider selection of powder and are able to use any powder they desire, and for the further reason that they can readily obtain a more copious supply of 25 powder on the puff than can be obtained from a compact. It has been difficult to satisfy this demand because there has not been available an entirely satisfactory vanity case in which to carry the loose powder. The loose powder would work out of the 30 vanity case and into the handbag and pockets or onto the dressing table, resulting in general untidiness. Too much of the loose powder adheres to the powder puff and shaking is generally resorted to for getting 35 rid of the excess supply of powder, even though this means wasting the powder, of which there is but a limited supply at hand.

40 An object of the present invention is to provide a vanity case for carrying loose powder, in which spillage is rendered practically impossible.

45 Another object of the invention is to provide such a vanity case for carrying loose powder with an arrangement in which only a limited amount of powder is permitted to get to the puff so that the puff can not be overloaded.

50 Another object of the invention is to provide a vanity case for loose powder in which the user can readily replenish the supply at will.

55 Another object of the invention is to provide a vanity case for loose powder in which the loose powder is retained underneath a perforate sifting device against which a puff

is adapted to be securely held when the vanity case is closed.

Another object of the invention is to mount the perforate sifting device in such a manner that its position does not depend 60 upon the amount of powder.

Another object of the present invention is to provide a vanity case wherein a perforate member is used to hold the powder in place; while permitting a plentiful supply to get 65 to the puff. This member is provided with an annular bead to cooperate with the puff to confine the powder and it may also be provided with slots or other means to assist removal for replenishing the powder supply. 70

Another object of the invention is to provide an improved method of controlling the quantity of loose powder which may be taken up by a powder puff.

In the accompanying drawings, there is 75 shown for the purpose of illustration, one of the many embodiments in which this invention may take form.

Fig. 1 is a transverse sectional view through the vanity case;

Fig. 2 is a plan view showing the perforate sifter member, and;

Fig. 3 is a section of the member shown in Fig. 2.

The vanity case has a powder receptacle 80 10 which is preferably made in the form of a round sheet metal stamping having a bottom 11 and cylindrical side walls 12. The side wall 12 is provided with an annular bead 13 and near its upper or open end 85 there are provided hinge and catch members 14 and 15, respectively, adapted to cooperate with the corresponding members 16 and 17 of a cover 18. The catch members 15 and 17 are such that they snap together 90 so as to securely hold the cover in position, and so that it can not be forced open by internal pressure. A perforate sifter member 19 is provided, the depending flange or side wall 20 of which, can freely slide down inside the cylindrical walls 12 of the powder containing stamping reaching the bottom 11. The member 19 is provided with a marginal imperforate portion and with a number of openings 21, which are shown in the form of 95 slots. They are located inside a peripheral upstruck bead 22 and extend toward the center of the member 19 so that the top of the member 19 is a grille. Of course, any other form of opening can be used instead 100

105 of slots. They are located inside a peripheral upstruck bead 22 and extend toward the center of the member 19 so that the top of the member 19 is a grille. Of course, any other form of opening can be used instead 110

of the slots illustrated, so long as they will accomplish the purpose set forth below. 65

It will be seen that the bead 22 provides a continuous upstanding flange which separates the perforate and imperforate portions of the member 19 and projects into the chamber which holds the puff. A couple of slots 23 which may be arc-shaped are cut in the central portion of the plate and the material 24, intermediate these slots, is preferably bent up as indicated in the drawing so that the user can conveniently slip the finger nail and thumb nail through the slots 23. In this manner the member 19 may be readily gripped and removed to replenish or change the supply of powder. 10

When the powder, indicated at 25, is placed in the sheet metal stamping 10 and the member 19 returned to the position shown, the user then places the puff or applicator 26 in place with the pile surface 27 next the member 19. The space below the mirror 28 and the top of the member 19 is such that the puff can be accommodated; but it will be held compressed by the cooperation of the catches 15 and 17 thereby forcing the puff directly against the bead 22 and forcing the pile of the puff into the slots 21. This is insured by the interengagement of the member 19 and the stamping 10 which prevents further movement of the member 19. Thus the vanity case is effectively sealed and the escape of powder from the compartment in which it belongs prevented. The vanity case can be carried in the pocket or handbag without fear of spilling the powder. 20 35

When one opens up the vanity case and takes out the powder puff, it is found that the design of the grille 21 is reproduced in the form of a powder stencil upon the surface of the powder puff. By making the perforations of a proper size, one can control the amount of powder which is stencilled upon the puff and the perforations can be so well proportioned that the amount of powder is sufficient for one application. The user opens up the vanity case, takes out the puff and uses it directly without shaking off an excess quantity of face powder. As loose powder is used, it is, of course, unnecessary to rub the puff upon a compact, which is more or less reluctant to give up the powder. 40 45 50

It has been found that, in carrying the vanity case in the pocket or handbag, the case is shaken about sufficiently to bring the powder to the puff. In the event that the user wants to make a second application, it is only necessary to close up the case with the puff in position, invert it and tap it slightly; then turn it right side up and open it. 55 60

It is, of course, obvious that the invention is susceptible of embodiment in double

vanity cases for both rouge and powder. 65

I claim:

1. A vanity case having a powder compartment open at the top, and a closure for the top, said closure being supported in spaced relation to the bottom of the compartment and having a grille, the open work of the grille being distributed about the surface of the closure to effect distribution of powder inside a raised peripheral bead which is adapted to engage a powder puff 70 75 to prevent the escape of powder.

2. In a vanity case, a powder compartment, having an open top, a perforate closure for the top, said closure fitting the inner wall of the compartment and being provided with a raised bead outside the perforations, which bead is adapted to engage a powder puff to prevent the escape of powder and a pair of slots adapted to receive the finger nails to permit its removal. 80 85

3. In a vanity case, a powder compartment having an open top, a closure for the top, said closure telescopically fitting the inner wall of the compartment and extending to the bottom of the compartment, and being provided with a grille and a raised bead outside the grille. 90

4. In a vanity case, a powder compartment, having an open top, a perforate closure for the top, said closure telescopically fitting the inner wall of the compartment and extending to the bottom of the compartment, and being provided with a raised bead outside the perforation, and a grip to permit its removal, the bead being adapted 100 to engage a powder puff to prevent the escape of powder. 10

5. A powder and puff case comprising a receptacle having powder and puff holding chambers, and a perforate partition separating said chambers and having an annular bead projecting into the puff holding chamber to engage the puff and thereby seal the powder holding chamber. 10

6. A powder and puff case comprising a receptacle having powder and puff holding chambers, a cover for the case, a powder puff, and a perforate partition separating said chambers and having an annular bead projecting into the puff holding chamber to engage the puff and thereby seal the powder holding chamber when the cover is closed. 11

7. In a vanity case, a powder compartment having an open top, a closure for the top, said closure telescopically fitting the inner wall of the compartment and extending to the bottom of the compartment, and being provided with a grille and a raised bead outside the grille, a hinged cover outside both the compartment and the closure, and a powder puff, said powder puff being held close to the closure to close the grille when the cover is closed, the grille and bead 11

being so disposed that powder cannot escape past the bead when the cover is closed onto the powder puff.

8. A vanity case having a receptacle for loose powder, a powder puff, a hinged cover, and an element against which the cover forces the puff when the cover is closed, said element having a raised bead adapted to engage the periphery of the puff to prevent the escape of powder, and a grille inside the bead.

9. A powder and puff case comprising a receptacle having a perforate partition dividing the receptacle into powder and puff holding chambers, said receptacle having a cover for the puff holding chamber and the

partition having an imperforate portion surrounding the perforate portion and the partition having a continuous upstanding flange separating the perforate and imperforate portions and projecting into the puff holding chamber. 20

10. A powder and puff case comprising a receptacle having powder and puff holding chambers separated by a partition, the partition having an upstanding annular flange spaced from its edge and having perforations inside of the flange, the portion of the partition outside of the flange being imperforate. 25

WILLIAM H. ROYSTONE.
